UNITED STATES PATENT OFFICE.

JOSEPH M. REDINGER, OF PROVIDENCE, RHODE ISLAND.

MILLING-MACHINE COLLET AND END MILL.

Application filed December 3, 1925. Serial No. 72,943.

This invention relates to certain new and useful improvements in milling machine collet and end mill, and the primary object thereof is to provide an improved construction which enables the cost of the high speed steel cutters to be maintained at a minimum.

The prevailing custom is to form the cutter and its holder in one piece with consequent high cost, the present invention aiming to provide a holder which can be made of cheap material thereby to reduce the cost of the cutter.

A further object of the invention is to provide a holder which may be used either with a double end cutter or mill or with a single end cutter, and to further provide a holder which effectively secures the cutter and holds same against rotation and which enables same to be easily applied and removed.

In the drawings:—

Figure 1 is a side elevation, partly broken away and in section;

Figure 2 is a section on line 2—2 of Figure 1;

Figure 3 is a section on line 3—3 of Figure 1;

Figure 4 is an end elevation of the cutter;

Figure 5 is a side elevation of a double ended cutter, and

Figure 6 is a like view of a single cutter.

In proceeding in accordance with the present invention, a holder is employed which consists of a shank 1 having a head 2 externally threaded at 3. The shank is formed with a bore 4 which latter has a bevelled or flared outer wall or end 5 that extends through the outer face of the head. A cap or nut 6 has a bore 7 of uniform diameter which closely fits over the smooth uniform-diametered part of the periphery of the head and which bore has threads 8 that engage with the threads 3 of the head. The outer end of the nut or cap is contracted and formed with a beveled wall 9 and with a circular shoulder 10. The usual wrench receiving holes 11 are also provided in the cap. The outer end face of the head is formed with preferably a pair of diametrically opposed openings 12 for a purpose now to be described.

In Figures 2 and 5 of the drawings a double end cutter is depicted and wherein a shank 13 has a cutter 14 on each end thereof. A central ring 15 is shrunk onto the

shank at the center thereof and is flanked on either side by bevelled rings 16, the taper of which latter rings corresponds to that of the beveled parts of the nut or cap and of the outer end of the holder. A pair of diametrically opposed wings 17 are carried by the central ring 15 and are receivable in the openings 12.

In Figure 6 of the drawings a single end cutter is illustrated, and wherein a shank 18 has a cutter 19 on one end and a central ring 20 flanked by bevelled rings 21, on its other end, the central ring having a pair of wings 22.

The three rings and the wings are identical with those shown in Figures 2 and 5 of the drawings.

In operation, with use of the double ended cutter, one of the cutters proper 14 is received in the bore 4 of the shank of the holder and in either use, i. e., of the double or single cutter, the wings 17 or 22 of the rings 15 or 20 are received in the openings 12 and the bevelled side rings are engaged with the bevelled wall 5 of the holder, and the bevelled wall 9 of the cap or nut. By tightening of the nut or cap, the central ring will be tightly clamped by and between the end wall of the holder and the shoulder 10 of the nut or cap and the bevelled side rings will also be tightly gripped by the walls 5 and 9, thus securely holding the cutter in position. The wings prevent rotation of the cutter, while the uniform bore of the cap or nut affords a firm seat or support therefor.

Having thus described my invention, what I claim as new and desire to secure by Letters Patent is:—

1. In a device of the type set forth, a holder having a shank formed with a bore and having a head formed with a flared opening, leading into the bore to form a bevelled wall, said head having a threaded peripheral portion and a smooth uniformed-diametered portion, the outer end face of the head being formed with a pair of opposed cut-outs, a cutter having a central ring provided with wings projecting outwardly from its periphery and received in the cut-outs, a bevelled ring on each side of the central ring, and one of which engages said bevelled wall of the head, and a nut threaded on the head and engaged with said smooth portion thereof and having a beveled wall to engage the outer bevelled ring.

2. In a device of the type set forth a

holder having a shank and a head, said head having a flared opening in its outer end forming a beveled wall and having a cut-out in the end face thereof, a cutter having a central ring provided with a wing received in said cut-out and having beveled rings on opposite sides of the central ring and one of which engages the beveled wall of the head, and a nut on the head having a beveled wall 10 to engage the outer ring.

3. In combination with a holder having a head formed with a flared socket and having an outwardly opening cut-out in its end, a cutter having a wing received in said cut-out 15 and having beveled parts on opposite sides of the wing and one of which parts engages the flared socket, and means on the head engaging the other of the beveled parts to secure the cutter to the head.

20 4. In combination with a holder having a head formed with a flared opening providing a beveled wall, a cutter having opposite and similarly beveled walls one of which engages the beveled wall of the head, inter- 25 engaging means independent of all of said walls between the cutter and head to hold the parts against relative turning, and a cap to secure the cutter to the holder and to hold the interengaging means against releasing 30 movement having a beveled wall engaging the other beveled wall of the cutter.

25 5. In combination with a holder having a head formed with a flared opening providing a beveled wall, a cutter having opposite 35 and similarly beveled walls, one of which engages the beveled wall of the head, a cap

to secure the cutter to the holder having a beveled wall engaging the other beveled wall of the cutter, and means independent of the cap to hold the cutter against turning movement. 40

6. In combination with a holder having a socket, a cutter having a pair of similar parts intermediate its ends, either of which is engageable in the socket, said holder having a cut-out providing opposed walls extending substantially axially of the holder, a projection on the cutter between said pair of parts thereof received between said walls and engageable in the socket in either position of 45 said parts and means to secure the cutter to the holder engageable with the other of said parts thereof. 50

7. In combination with a holding element having a socket, a cutting element having a pair of similar parts intermediate its ends, either of which is engageable in the socket, complementary means on the holding element and on the cutting element and disposed between said pair of parts of the latter 55 to hold the cutting element against rotation relative to the holding element in either position of said parts including spaced opposed walls extending axially of one of said 60 elements and a part on the other of said elements received between the walls, and means to secure the cutting element to the holding element engageable with the other of said 65 parts thereof.

In testimony whereof I have signed my name to this specification.

JOSEPH M. REDINGER.
